FIG. 1

FIG. 2

FIG. 3

FIG. 4

FIG. 1 is a perspective view of an extension table showing my new design, the table being in the closed position, with the extension leafs in stored position.

FIG. 2 is a fragmented section view taken along line 2-2 of FIG. 1.

FIG. 3 is an end elevation view, the two ends being the same.

FIG. 4 is a perspective view corresponding to FIG. 1, but with the table in the extended position by incorporation of the two extension leafs with a cut-away portion on the table top.

I claim:

The ornamental design for an extension table or similar article, as shown.
